UNITED STATES PATENT OFFICE.

BARTON W. SCOTT, OF SAN JOSÉ, ASSIGNOR TO HIMSELF, AND WILLIAM RICE, OF SARATOGA, CALIFORNIA.

WRITING-TABLET AND MANUSCRIPT-HOLDER.

SPECIFICATION forming part of Letters Patent No. 508,349, dated November 7, 1893.

Application filed January 17, 1893. Serial No. 458,638. (No model.)

To all whom it may concern,

Be it known that I, BARTON W. SCOTT, of San José, in the county of Santa Clara and State of California, have invented a new and 5 Improved Writing-Tablet and Manuscript-Holder, of which the following is a full, clear, and exact description.

The object of the invention is to provide a new and improved hand actuated writing tablet and manuscript holder, which is simple and durable in construction, and more especially designed for the use of stenographers, writers, public speakers, type setters and others, and arranged to permit of conveniently 10 writing subject matter on a continuous sheet or web of paper, and displaying the written matter in the proper position either for the speaker when delivering the speech, or for the copyist when copying, or the type setter to 15 work from or for other purposes.

The invention consists of a casing provided with two winding drums for the paper, a main shaft journaled in the casing, and two sets of gear wheels actuated from the said shaft, and 20 adapted to be geared with the said winding drums.

The invention also consists in certain parts and details, and combinations of the same, as will be hereinafter described and then pointed 25 out in the claims.

Reference is to be had to the accompanying drawings, forming a part of this specification, in which similar letters of reference indicate corresponding parts in all the figures.

30 Figure 1 is a perspective view of the improvement showing the cover of the casing open. Fig. 2 is a transverse section of the same on the line 2—2 of Fig. 5, with the cover closed. Fig. 3 is an enlarged rear face view 35 of the driving shaft and parts connected therewith. Fig. 4 is a side elevation of the tripping mechanism for the brake mechanism, parts being in section. Fig. 5 is a plan view of the casing and contents with the 40 cover top, frame and table removed. Fig. 6 is a transverse section of a clutch mechanism for the tripping device. Fig. 7 is a face view 45 of the clutch wheel. Fig. 8 is a longitudinal sectional side elevation of the improvement 50 on the line 8—8 of Fig. 5. Fig. 9 is a similar view of the same on the line 9—9 of Fig. 5.

Fig. 10 is a longitudinal section of the improvement on the line 10—10 of Fig. 5. Fig. 11 is a transverse section of part of the improvement on the line 11—11 of Fig. 8, and 55 Fig. 12 is a rear side elevation of the mechanism for shifting the paper line by line.

The improved writing tablet and manuscript holder is provided with a casing A preferably made of a light sheet metal, such as 60 aluminum or other material, the casing being arranged in the shape of a book as plainly illustrated in Fig. 1, with one of the covers A' arranged to swing open to present a rectangular frame A² hinged at A³ to the top edge 65 of the rear side A⁴ of the casing A, the front end of the said rectangular frame A² resting on the top edge of the front side A⁶, as plainly shown in the drawings. This hinged frame A² is locked in place at the front side by a 70 spring pressed latch A⁵ pivoted to the inside of the front side A⁶. Under the rectangular frame A² is arranged a table B over which passes the paper C made in a continuous sheet or web and on which the subject matter is written or the matter written thereon is read from, in delivering a speech or copying the subject matter, as the case may be. The table B is supported at its front on posts B', erected inside of the casing A, at the front 75 side A⁶ thereof, as plainly shown in Fig. 2, the rear side of the said table resting on a longitudinally-extending partition A⁷ formed in the casing near the rear end A⁴, as plainly illustrated in Figs. 2 and 5.

80 The front and rear ends of the table B are bent downward to form flanges B² fitting over the posts B', and the partition A⁷ to securely hold the said table in place. The table B is preferably made of a light sheet metal and is 85 strengthened on its under side by a series of transversely-extending ribs B³, as plainly indicated in Figs. 2, 9 and 10. The front and rear sides of the table B project beyond the opening of the frame A², while the ends of the said table do not quite reach to the ends of the frame opening, as will be readily understood by reference to Figs. 8 and 9.

90 The paper C is in the form of a continuous sheet of any desirable length, and is adapted 95 to be wound up or unwound from a transversely-extending paper drum D, from which 100

the paper passes over a roller E located in the upper end of the casing A and journaled at its ends in the front side A⁶ and the partition A⁷ of the said casing, as plainly shown in Fig. 5.

5 The top of the roller E is in alignment with the top of the table B, so that the paper passes from the roller onto and over the top of the table B, to finally pass from the lower end of the latter under the frame A² upon a 10 second roller F arranged transversely in the lower end of the casing A and likewise journaled in the front and rear sides of the casing A. The paper passes from the lower end of the roller F to a paper drum G arranged 15 in front of the roller F and extending transversely, parallel to the other drum D and the rollers E and F, as will be readily understood by reference to Fig. 5. The ends C' C² of the paper C are held in place on the shafts D 20 and G by a suitable clamping spring, see Fig. 5, or other device. Now, it will be seen that when the paper drum G is turned in the direction of the arrow a', then the paper C is wound on the said drum and unwound from 25 the drum D, the paper passing over the table B in the direction of the arrow b'. When, however, the drum D is rotated in the direction of the arrow c', then the paper winds up on the drum D and unwinds from the drum 30 G, the paper then passing over the table B in the inverse direction of the arrow b'.

In order to impart the movement described to the paper drums D and G, I provide a hand actuated mechanism partly arranged within 35 the casing A and part on the rear side thereof, as plainly illustrated in the drawings. This mechanism serves to rotate the drums D and G in the directions mentioned, for imparting a traveling motion to the paper C in 40 either a forward or backward direction, that is, in the direction of the arrow b' or the inverse direction thereof. This hand actuated mechanism is provided with a transversely-extending shaft H journaled in suitable bearings arranged on the front and rear sides A⁶ and A⁴ respectively, the said shaft being located between the drums G and D, as plainly 45 illustrated in Fig. 5. The forward end of the shaft H projects into a recess formed on the 50 outside of the front side A⁶ of the casing A, as shown in Figs. 1 and 2, and this outer end of the shaft is made square as at H', for receiving a key to conveniently turn the said shaft for the purpose hereinafter more fully 55 described.

Near the rear end of the shaft H, at the back of the partition A⁷ is secured a gear wheel H² adapted to actuate two trains of gear wheels I and J, of which the train of 60 gear wheels I is adapted to be geared with the drum D, and the other train of gear wheels is adapted to be geared with the paper drum G. The train of gear wheels I is arranged on one side of the gear wheel H², and is provided with 65 a pinion I' in mesh with the said gear wheel H² and mounted to rotate on a shaft I² held in the partition A⁷, and the rear side A⁴. On

the hub of this pinion I' is secured a large gear wheel I³ in mesh with a pinion I⁴ mounted to rotate on a shaft I⁵ also held in the partition A⁷ and the side A⁴. On the hub of this pinion I⁴ is secured a large gear wheel I⁶ adapted to be engaged by a pinion D' secured on the reduced end D² of the shaft of the drum D. The rear reduced end of this shaft D² is journaled in suitable bearings held in a lever D³ arranged vertically and pivoted at its lower end at D⁴ to the inner surface of the rear side A⁴ of the casing A. The upper end of the lever D³ is reduced to form a handle which extends through an opening A⁸ in the rear side of the frame A², see Figs. 1 and 8, so that the end of this lever can be taken hold of on top of the casing A by the operator when the cover A' is swung back. The longitudinal swinging motion of the lever D³ is limited by a stop pin, or projection (not shown) secured on the back of the lever D³ near its handle end, the said pin or projection being adapted to engage either of two notches or dents D⁵ and D⁶ formed in the rear side A⁴, as shown in Fig. 8. Now, it will be seen that when the lever D³ is moved to the left, the pinion D' is thrown in mesh with the gear wheel I⁶ and when the shaft H is rotated and the train 90 of gear wheels I is set in motion thereby, then a rotary motion is given to the said pinion D' and consequently to the paper drum D which latter then revolves in the direction of the arrow c', to wind up the paper. The other train 95 of gear wheels J for the drum G is similarly constructed to the train of gear wheels I, and is arranged on the opposite side of the wheel H² to that on which the train of gear wheels I is located. This train of gear wheels J is provided with a pinion J' in mesh with the gear wheel H², and mounted to turn on a shaft J² held in bearings in the partition A⁷ and the rear side A⁴. On the hub of this pinion J' is secured a large gear wheel J³ in mesh 100 with a pinion J⁴ held on a shaft J⁵ journaled in the said partition A⁷ and rear side A⁴. On the hub of this pinion J⁴ is secured a large gear wheel J⁶ adapted to be engaged by a pinion G' held on the reduced end G² of the 105 shaft of the drum G. The rear reduced end of this shaft G² is journaled in suitable bearings in a lever G³ arranged vertically and pivoted at its lower end at G⁴ to the inner surface of the rear side A⁴ of the casing A. The upper end of this lever G³ is reduced to form a handle which extends through an opening A⁹ in the rear side of the frame A², see 110 Figs. 1 and 8; so that the end of this lever can be taken hold of on top of the casing A by the operator, whenever the cover A' is swung back. The longitudinal swinging motion of the lever G³ is limited by a stop pin arranged at the back of the lever G³, see Fig. 11, and adapted to engage a dent G⁵ arranged on one side of the handle end of the said lever, see Fig. 8, and formed in the rear side A⁴. Now, it will be seen that when the lever G³ is moved to the right its pinion G' is thrown in 115 120 125 130 135

mesh with the gear wheel J^6 , and as the latter receives a rotary motion when the main driving shaft H is turned, a rotary motion is given to the drum G to wind up the paper thereon for the purpose hereinafter more fully described.

In order to rotate the paper drum D for shifting the paper line by line, I provide the mechanism K arranged in the upper end of the casing A between the partition A^7 and the rear side A^4 ; see Figs. 5, 8 and 12. When the lever D^8 is moved to the right, the pinion D' is thrown in mesh with a large gear wheel K' mounted to rotate loosely on a short shaft K^2 held in suitable bearings in the partition A^7 on the side A^4 . A lever K^3 is loosely fulcrumed on the shaft K^2 and is provided with an upward extension adapted to pass through a notch formed in the frame A^2 near the opening A^8 , as shown in Figs. 1 and 8. The outer end of this extension of the lever K^3 carries a button K^4 adapted to be pressed on by the operator. On the lever K^3 is held a spring pressed pawl K^5 engaging the gear wheel K' , so that when the button K^4 is pressed, the said lever K^3 swings downward and the pawl K^5 imparts a rotary motion to the gear wheel K' , which on account of being in mesh at the time with the pinion D' , rotates the paper drum D in the direction of the arrow c' , to wind up the paper thereon. A spring K^6 is connected with the lever K^3 to draw the latter back into its uppermost position, as soon as the pressure on the button K^4 ceases. A dog K^7 engages the gear wheel K' to prevent a return movement of the latter. The distance the button K^4 is pressed down regulates the distance the sheet of paper C is wound on the paper drum D . Usually however, the button K^4 is pressed such a distance as to move the paper forward the distance between two lines on the paper, so that every time the button K^4 is pressed a new line is presented to the operator writing on the paper, the hand being supposed to be stationary.

When the lever D^8 is in a vertical position, as shown in Fig. 8, its pinion D' is out of mesh with either the gear wheel I^6 or the gear wheel K' . This intermediate position of the lever D^8 is necessary so that the paper can unwind from the paper drum D and wind up on the drum G , as before mentioned at the time the shaft H is turned. In a like manner, the pinion G' is held out of mesh as shown in Fig. 8, at the time the pinion D' is in mesh with its gear wheel I^6 for the purpose of winding up the paper on the drum D .

In order to return the paper the distance of one page at a time, the page being considered the amount displayed in the opening of the frame A^2 , a device L is provided having a segmental bevel gear wheel L' mounted to rotate loosely on the rear end of the shaft H and in mesh with a like segmental bevel gear wheel L^2 secured on a longitudinally-extending shaft L^3 mounted to turn in suitable bearings L^4 attached to the rear side A^4 of the cas-

ing A . The shaft L^3 extends with its lower square end L^5 to the lower end of the casing A and this square end L^5 is adapted to be engaged by a key L^6 having a finger piece, as indicated in dotted lines in Fig. 5. A coil spring L^7 attached at one end to a bar secured on the casing A is connected at its inner end with one side of the bevel gear wheel L' , so that when the spring is wound up on turning the gear wheel the latter will automatically return by the action of the spring L^7 .

In order to connect the bevel gear wheel L' with the gear wheel H^2 , to rotate the latter in one direction only, I provide the rear face of the said gear wheel with an annular flange H^3 ; see Fig. 3. On the hub of the bevel gear wheel L' are formed arms L^8 extending in opposite directions and each carrying a brake shoe L^9 adapted to engage the inner surface of the said annular flange H^3 . A spring L^{11} held on the respective arm L^8 presses against the brake shoe L^9 to hold the same in frictional contact with the flange H^3 . Now, it will be seen that when the gear wheel L' is turned in one direction, the brake shoes L^9 remain out of frictional contact with the flange H^3 , but when the said gear wheel L' is turned in the opposite direction, the brake shoes L^9 engage the said annular flange and carry the same along, thus turning the gear wheel H^2 which, by its connection with the train of gear wheels I actuates the latter to revolve the drum D sufficiently to turn the paper C , the distance of one page.

In order to keep the mechanism locked during the time the paper is to remain at a standstill, I provide a brake mechanism N under the control of the operator. This brake mechanism N is provided with a brake shoe N' adapted to be held in frictional contact with the periphery of the gear wheel J^6 of the train of gear wheels J , see Figs. 5 and 8. The brake block N' is held on a pin N^2 projecting from the brake lever N^3 arranged between the partition A^7 and the rear side A^4 , the fulcrum of the lever being on the partition. A spring N^4 secured on the casing is connected with the said lever N^3 , so as to move the latter upward to hold the brake shoe N' in frictional contact with the wheel J^6 so as to lock the said train of gear wheels in position. The free end of the brake lever N^3 is pivotally connected with an arm N^5 connected by an articulated joint N^6 with one arm of a bell crank lever N^7 pivoted to the casing and provided on its upper arm with a button N^8 projecting through a recess in one edge of the frame A^2 , so that the said button is under the control of the operator.

A tripping mechanism O actuated from the roller F is connected with the brake mechanism N and for this purpose the lower or downwardly-extending arm of the bell crank lever N^7 is provided with a friction roller N^9 and a fixed L-shaped arm L^{11} adapted to engage opposite sides of the cams O' and O^2 formed on

the front face of the gear wheel O^3 mounted to rotate loosely on a short shaft O^4 journaled in the partition A^7 and the rear side A^4 of the casing A . The gear wheel O^3 is in mesh with 5 a pinion O^5 mounted to rotate loosely on the shaft F' of the roller F , the said pinion O^5 being provided at its front face with a series of recesses O^6 arranged in a circle, see Fig. 7, and adapted to be engaged by a pin P' projecting rearwardly from the rear face of a grooved shifting wheel P mounted to slide on and to turn with the shaft F' of the roller F , as plainly illustrated in Figs. 5 and 6. The hub P^2 of the wheel P is provided for this purpose with a slot P^3 engaged by a pin P^4 fastened to the shaft F' , the said pin permitting the wheel P to slide to engage the pin P' with one of the apertures O^6 and at the same time the pin P^4 causes the wheel P to revolve at 10 the time the roller F is turned by the traveling paper unwinding from the drum G and winding up on the drum D . The groove in the periphery of the wheel P is engaged by a pin P^5 projecting from a lever P^6 fulcrumed 15 at its lower end at P^7 on the rear side A^4 as plainly shown in Fig. 8. The upper end of this lever P^6 extends through an aperture A^11 in the frame A^2 , so that the outer end of the lever is under the control of the operator, who 20 can shift the lever transversely to move the pin P' in or out of contact with one of the apertures O^6 . In order to lock the lever P^6 in either an inward or outward position I engage the said lever with notches P^8 and P^9 , 25 formed in a bar P^{11} extending transversely and secured on the partition A^7 , and the rear side A^4 , as illustrated in Fig. 5. When the paper travels over the roller F at the time the paper winds up on the drum D , and when 30 the lever P^6 is shifted transversely to move the pin P' in contact with an aperture O^6 in the gear wheel O^5 , then the latter is rotated with the said roller F and imparts a rotary motion to the gear wheel O^3 , so that the cams 35 O' and O^2 on the said gear wheel O^3 can act on the friction roller N^9 so as to open the articulated joint N^6 connecting the arm N^5 with the bell crank lever N^7 . This is done to stop the traveling motion of the paper at the time 40 the latter moves in the inverse direction of the arrow b' and has moved the distance of one page, that is, the distance exposed to view in the opening of the frame A^2 . When the lever N^8 is in its usual position as shown in Fig. 45 45, then the brake shoe N' is supplied on the gear wheel J^6 , the button N^8 of the bell crank lever N^7 then being in an uppermost position. Now, when it is desired to rotate the drum G by the train of gear wheels J , the latter must 50 be unlocked by releasing the brake shoe N' on the periphery of the gear wheel J^6 . This is done by the operator pressing the button N^8 so that a swinging motion is given to the bell crank lever N^7 which, by its connection 55 with the arm N^5 pivoted to the lever N^8 , causes the latter to swing downward, thus moving the brake shoe N' out of frictional

contact with the wheel J^6 . It is understood that when the wheel P is with its pin P' out of contact with the gear wheel O^6 , the latter as well as the gear wheel O^3 is at a standstill and the cams O' and O^2 are out of action as regards the opening and closing of the articulated joint N^6 connecting the arm N^5 with the bell crank lever N^7 . The paper on the under side of the roller F is pressed in contact with the latter near the middle by a roller Q made of felt or other suitable soft material and journaled in a frame Q' projecting from a transversely-extending shaft Q^2 mounted to turn in suitable bearings arranged in the front side A^6 and partition A^7 . A spring Q^3 is coiled on the said shaft Q^2 and fastened with one end to the side A^6 and at its other end on a pin secured on the shaft Q^2 , so as to hold the roller Q always in contact with the under side of the paper C to press the latter against the roller F . The latter, as well as the roller E in the upper part of the casing A , is preferably covered with rubber or other suitable elastic material to increase the adhesion of the paper on the said rollers to prevent slipping. A brake shoe S presses the paper on the paper drum G , the said brake shoe being arranged on the under side of the paper and secured on an arm S' projecting from a transversely-extending shaft S^2 journaled in suitable bearings in the side A^6 and the partition A^7 . A spring S^3 is coiled on one end of the shaft S^2 and secured at one end to a disk S^4 fixed to the side A^6 and provided with a series of apertures S^5 one of which is engaged by the end of the spring. The latter is attached at its other end to a pin on the said shaft S^2 , the said spring serving to hold the arm S' upward to move the brake shoe S in firm contact with the paper on the increasing and diminishing of the roll of paper, as it accumulates or lessens on the drum G . The disk S^4 serves to increase or decrease the tension of the spring S^3 .

The bearings T for the shafts of the drums G and D , and the shafts of the rollers E and F on the front side A^6 , are preferably of the construction illustrated in Fig. 10, each bearing T being formed with a semi-circular lower seat part T' and a beveled top part T^2 secured in a spring T^3 fastened to the lower part T' . One side of the latter is slightly beveled so as to form a V-shaped groove when the upper part T^2 is over the seat for the shaft, as plainly shown in Fig. 9. Now, it will be seen that in order to place one of the shafts in its bearing T , the end is simply passed down the beveled parts of the bearing so that the upper part T^2 finally swings to one side, its spring T^3 permitting such movement until the shaft has dropped into the opening in the lower part T' . The spring pressed upper part T^2 then snaps over the end of the shaft and holds the same securely in place in the bearing. As previously described, the opposite bearings of the shafts G and D are in the levers G^3 and D^3 respectively.

The operation is as follows: In using the machine for writing on the paper C, the operator places his right hand and pen or pencil on the manuscript paper in the position 5 most convenient for him, with his left hand on the open cover A', so as to hold the latter in an open position. The operator then places the left forefinger on the button K⁴ held in an uppermost position by the spring K⁶ and 10 on pressing the said button the lever K⁸ by its pawl K⁵ turns the gear wheel K' in mesh with the pinion D', so that the paper drum D winds up the paper, the drum turning in the direction of the arrow c', and the paper moving 15 over the table B in the inverse direction of the arrow b'. Now, as soon as the operator has finished a line he presses the button K⁴ down again to move the paper forward the distance of one or two lines according to the depth the 20 button K⁴ is depressed. The paper C is of sufficient length to enable a reporter or other person to note down a lengthy speech or other matter, it being understood that the paper is shifted in the inverse direction of the arrow 25 b' one or two lines at a time on pressing the button K⁴. Now, in case the operator desires to review and correct writings wound up on the paper drum D, he throws the lever D⁸ into an intermediate position and moves the 30 lever G⁸ to the right, so as to bring the pinion G' in mesh with the gear wheel J⁶ and then applies a key on the square end H' of the shaft H to turn the latter so as to actuate the train of gear wheels J to revolve the drum 35 G, which rewinds the paper, the latter then traveling in the direction of the arrow b'. It is understood that the paper now unwinds from the paper drum D and travels over the table B. When the paper has finally been 40 wound up again on the paper drum G the first line the operator has written again appears in the opening of the frame A² and the party desires to correct or read off the written matter or to copy the same page by page, he 45 then moves the lever G⁸ to the left to disengage the pinion G' from the gear wheel J⁶ and moves the lever D⁸ to the left to move its pinion D' in gear with the gear wheel I⁶. The operator also moves the lever P⁶ transversely 50 to connect the shaft F' of the roller F with the pinion O⁵ by the shifting wheel P engaging with its pin P' one of the apertures O⁶ of the said pinion O⁵. Now, as soon as the operator has read or copied the first page as it appears 55 in the opening of the frame A², he presses with his finger the key L⁶ downward, so that the shaft L³ is rotated and the gear wheel L² meshing in the gear wheel L' rotates the latter to wind up the return spring L⁷, the 60 brake shoes L⁹ then being off the annular flange H³ of the gear wheel H'. As soon as the operator releases the pressure on the key L⁶, the wound up spring L⁷ causes its gear wheel L' to return, at the same time carrying 65 along the arms L⁸ and the brake shoes L⁹, which now clutch the flange H³, thus rotating the gear wheel H' and the latter by its con-

nexion with the train of gear wheels I and the pinion D' in mesh with the gear wheel I⁶ of the said train of gear wheels, causes the 70 drum D to rotate in the direction of the arrow c' to wind the paper thereon. The several parts described are so arranged and geared in proportion, that the return movement of the spring will shift the paper the 75 distance of one page, so that the second page of the manuscript will be displayed in the opening of the frame A². The roller F which is rotated by the paper traveling in the inverse direction of the arrow b' causes the gear 80 wheel O³ carrying the cams O' and O² to make one-half revolution for each page of manuscript, so that the cams O' and O² act on the bell crank lever N⁷ by one of the cams coming in contact with the friction roller N⁹ and 85 the arm N¹¹ so as to hold the brake shoe N' off the wheel J⁶ until the paper has traveled the distance of one page, after which the friction roller N⁹ and the arm N¹¹ pass off the respective cam to again permit the spring 90 N⁴ to swing the lever N⁸ upward, so as to apply the brake shoe N' on the gear wheel J⁶ to stop the actuating mechanism at the time the bottom of the first page disappears in the upper end of the opening of the frame A². 95 It is understood that during the return movement of the gear wheel L' caused by the action of the spring L⁷, both trains of gear wheels I and J are rotated from the gear wheel H² and it is necessary to unlock the train of gear 100 wheels J by releasing the brake shoe N', the operator pressing the button N⁸ for that purpose, as previously explained. It will be seen that by this arrangement page after page is displayed in the opening of the frame A², the 105 operator only having to press the key L⁶ downward to wind up the return spring L⁷ which on the release of the key actuates the mechanism as described. It will further be seen that in this manner the machine will display 110 before a public speaker his notes or his full manuscript, for use in delivering the speech or the entire matter is presented before a type setter as his copy, or before a player of a musical instrument as his music. 115

Having thus fully described my invention, I claim as new and desire to secure by Letters Patent—

1. In a device of the class described, the combination with a main driving shaft carrying a gear wheel, of two trains of gear wheel connected with the said main shaft gear wheel, paper drums adapted to be thrown in mesh with the said trains of gear wheels, and a spring mechanism connected with the said 120 main shaft gear wheel a depressing key to wind the spring, and means whereby on releasing the key the compressed spring actuates the said main shaft gear wheel and the trains of gear wheels, substantially as shown 125 and described.

2. In a device of the class described, the combination, with a casing provided with a 130 table over which passes the paper to appear

- in an opening formed in the top of the casing, of a main driving shaft adapted to be turned by hand and carrying a gear wheel, a spring mechanism connected with the said gear wheel, a depressing key to wind the spring, two trains of gear wheels in mesh with the said main shaft gear wheel, two paper drums journaled in the said casing parallel to the main shaft and adapted to be thrown in mesh with the said trains of gear wheels, and a brake mechanism connected with one of the said trains of gear wheels to lock the driving mechanism, substantially as shown and described.
15. 3. In a device of the class described, the combination with a casing provided with a table over which passes the paper to appear in an opening formed in the top of the casing, of a main driving shaft adapted to be turned by hand and carrying a gear wheel, two trains of gear wheels in mesh with the said main shaft gear wheel, two paper drums journaled in the said casing and adapted to be thrown in mesh with the said trains of gear wheels, a brake mechanism connected with one of the said trains of gear wheels to lock the driving mechanism, and a tripping mechanism, substantially as described, for automatically unlocking the said brake mechanism to hold the 30 brake shoe off its brake wheel during the time the paper runs back over the table the distance of one page, as set forth.
4. In a device of the class described, the combination with a main driving gear wheel 35 provided with an annular flange, of a segmental gear wheel mounted to rotate loosely on the shaft of the said main gear wheel, a spring connected with the said segmental gear wheel and adapted to be wound up by the latter, and brake shoes pivoted upon arms pro-

jecting from the said segmental gear wheel, the said brake shoes being adapted to engage the annular flange of the said driving gear wheel, substantially as shown and described.

5. In a device of the class described, the combination with a main driving gear wheel provided with an annular flange, of a segmental gear wheel mounted to rotate loosely on the shaft of the said main gear wheel, a spring connected with the said segmental gear wheel and adapted to be wound up by the latter, brake shoes pivoted upon arms projecting from the said segmental gear wheel, the said brake shoes being adapted to engage the annular flange of the said driving gear wheel, 55 and springs pressing on the said brake shoes, substantially as shown and described.

6. In a device of the class described, the combination with a main driving gear wheel provided with an annular flange, of a segmental gear wheel mounted to rotate loosely on the shaft of the said main gear wheel, a spring connected with the said segmental gear wheel and adapted to be wound up by the latter, brake shoes pivoted upon arms projecting from the said segmental gear wheel, the said brake shoes being adapted to engage the annular flange of the said driving gear wheel, 60 a shaft carrying a segmental gear wheel in mesh with the first named segmental gear wheel, and a key held on the said shaft and adapted to be pressed on by the operator to rotate the shaft and the segmental gear wheels to wind up the spring, substantially as shown and described.

BARTON W. SCOTT.
